United States Patent Office

Des. 228,806
Patented Oct. 23, 1973

228,806

FRAME FRONT FOR SPECTACLES

Charles R. Harrell, 4256 Lyceum Ave.,
Los Angeles, Calif. 90066

Filed Oct. 12, 1971, Ser. No. 188,636

Term of patent 14 years

Int. Cl. D16—06

U.S. Cl. D57—1 F

FIG. 1.

FIG. 2.

FIG. 3.

FIG. 4.

FIG. 1 is a front perspective view of a frame front for spectacles showing my new design;

FIG. 2 is a top plan view thereof;

FIG. 3 is a rear perspective view thereof; and

FIG. 4 is a front elevation thereof.

I claim:

The ornamental design for a frame front for spectacles, as shown and described.
